UNITED STATES PATENT OFFICE.

HERBERT HENDERSON AND JOHN G. GLASGOW, OF PORT ARTHUR, TEXAS, ASSIGNEES
TO GULF REFINING COMPANY, OF PITTSBURGH, PENNSYLVANIA, A CORPORATION
OF TEXAS.

HEAT EXCHANGER.

Application filed September 4, 1926. Serial No. 133,612.

This invention relates to heat exchangers and specifically to a heat exchanger comprising a fixed casing through which a fluid is circulated, a plurality of tubes extending axially of said casing through which another fluid is conducted, said tubes being fixedly attached, at one end, to said casing and at their other ends being affixed to a flanged tube plate to which a cover plate is detachably secured. The flanged tube plate and cover form a floating head which is movable relative to the casing whereby said tubes can expand or contract independently of said casing. Means are provided coacting with said floating head and casing permitting movement of one relative to the other but maintaining a fluid tight seal therebetween; all as more fully hereinafter set forth and as claimed.

In heat exchangers the tubes are subject to expansion and contraction due to changes in their temperature. It has accordingly been proposed to provide a floating head for such tubes to permit of their expansion and contraction independently of the casing or shell within which they are mounted to thus prevent warping of the tubes or bursting of the shell. One fluid is conducted through the tubes of the exchanger and a second fluid of different temperature is circulated through the casing around the tubes. It is imperative that no leaks occur which would permit commingling of the different fluids, and they must therefore be kept separated while at the same time a relative movement of the parts of the heat exchanger is permitted. The present invention accomplishes this by the provision of a metallic bellows which is fastened at one end to the fixed shell of the exchanger, and at its other end to the floating head. Packing is interposed between the cover plate and the flange of the tube plate, and likewise between the cover plate and the bellows at its point of attachment thereto. Thus, when the tubes expand and the face plate and floating head move the bellows will be expanded but regardless of the amount of expansion, a fluid tight seal is always provided.

It is an object of our invention to provide a heat exchanger comprising a casing and tubes therein with means for permitting ex-

pansion of the tubes relative to the casing, yet maintaining a fluid tight seal between them. Other and further objects will be apparent from the following description and the drawings in which:

Figure 1 is a fragmentary cross-sectional view of one end of a heat exchanger showing one embodiment of our invention.

Figure 2 is a sectional view of a modified form of structure showing one end of a heat exchanger.

Figure 3 is an end view of the modified form of heat exchanger shown in Figure 2.

Figure 4 is a sectional view of an entire heat exchanger.

A fixed casing 1 has mounted therein a plurality of tubes 2 which are fixedly attached to it at one end (not shown) and at their other ends are securely affixed to a support or tube plate 3 which is formed with an integral flange 4. A cover plate 5 is detachably secured to the flange of the tube plate as by bolts 6 and is provided with an opening 7 for the introduction of a fluid into the tubes. The tube plate 3, flange 4 and cover 5 form a floating head which is free to move relative to the casing. A ring 8 surrounds the flange 4 and is secured to the cover 5 by means of bolts 9. Packing 10 and 11 is interposed between the cover 5 and the ring and flange respectively. Ring 8 has affixed thereto a metallic bellows 12 the opposite end of which is secured, as by bolts 13, to a flange 14 screwed upon or otherwise affixed to the casing of the exchanger.

A modified construction is shown in Figures 2 and 3 wherein the fixed casing 15 has a plurality of tubes 16 extending therethrough, securely fixed at one end (not shown) to the casing and at their other ends to a support or tube plate 17 having an integral flange 18 similar to that hereinbefore described. A flanged member 19 is affixed to the casing at its end and is internally grooved as at 20 for the reception of a packing 21, compressed by a gland 22, which is adjusted by a series of bolts 23. The member 19 is further provided with spaced radial projections 24 bored to receive guides 25 which are adapted to extend through openings in a cover plate 26. The cover plate is detachably secured to flange

18 by a plurality of bolts 27. In this construction the packing 21 provides an efficient seal against leakage of fluid to the outside of the exchanger or its commingling 5 with the liquid conducted through the tubes, yet permits expansion and contraction of the tubes relative to the casing or shell. The guides which cooperate with the cover plate serve to keep the movable tube plate 10 and tubes in alignment with the casing and, by assisting in supporting the weight thereof, they prolong the life of the packing by preventing its uneven wear. When, however, the packing becomes worn or loose any 15 leakage which occurs will be at once discovered because it will be visible on the outside of the exchanger, and can consequently be remedied without loss or contamination of the liquids treated by tightening of the gland or replacement of the 20 packing.

From the foregoing it will be apparent that we have provided a simple and efficient heat exchanger, which permits of expansion and contraction of the tubes relative to a fixed outer shell or casing, but which prevents leakage and the commingling of separated bodies of fluid.

What we claim is:—

30 1. A heat exchanger comprising a fixed casing, a series of tubes extending axially of said casing and fixedly attached thereto at one end, a flanged tube plate at the opposite end of said casing in which the 35 ends of the tubes are fixedly mounted, a cover plate detachably secured to the flange of said tube plate, and an expansible bellows fastened to said cover plate and fixed casing to permit expansion and contraction 40 of said tubes within the casing yet maintaining a fluid-tight seal between them.

2. A heat exchanger comprising a fixed casing, a series of tubes in said casing fixedly attached thereto at one end, a tube plate 45 in which the opposite ends of said tubes are fixed, said tube plate being flanged to extend beyond the end of the casing, a removable cover plate secured to the flange of said tube plate thereby forming a float-

ing head, a metal bellows fastened at one 50 end to the end of said casing and at its other end to said floating head whereby expansion and contraction of the tubes causes expansion and contraction of the bellows thus permitting the tubes to move relatively 55 to the casing but maintaining a fluid-tight seal therebetween.

3. A heat exchanger comprising a fixed casing, a series of tubes extending through said casing and fixedly attached thereto at 60 one end, a flanged tube plate at the other end of said casing in which the ends of the tubes are fixedly mounted, said tube plate being movable relative to the casing on expansion and contraction of the tubes, a cover 65 plate detachably secured to the flange of said tube plate, and means fixed to the exterior of said casing and to said cover plate and cooperating with said tube plate for maintaining a fluid-tight seal between said cas- 70 ing and tube plate.

4. A heat exchanger comprising a casing through which a fluid is circulated, a series of tubes in said casing through which another fluid is circulated, a support for the 75 ends of said tubes adapted to move relative to the casing when the tubes expand and contract, fluid tight sealing means between said support and the casing, radial projections extending from the casing and from 80 the cover plate, and guides extending through said projections.

5. A heat exchanger comprising a casing through which fluid is circulated, radially extending arms connected to the casing, a 85 series of tubes inside the casing, a support for the ends of the tubes adapted to move relative to the casing, radially extending arms attached to said support and in line with the arms of said casing and guide 90 means arranged through the casing arms and the support arms whereby the arms of the tube supports may move over said guides when the tubes contract and expand.

In testimony whereof, we have hereunto 95 affixed our signatures.

HERBERT HENDERSON.
JOHN G. GLASGOW.
